UNITED STATES PATENT OFFICE.

JOSEPH T. WARD AND JOHN B. CURTIS, OF CHICOPEE FALLS,
MASSACHUSETTS.

COVER-LOCKING DEVICE FOR COTTON-BEATERS.

SPECIFICATION forming part of Letters Patent No. 633,930, dated September 26, 1899.

Application filed July 5, 1899. Serial No. 722,816. (No model.)

To all whom it may concern:

Be it known that we, JOSEPH T. WARD and JOHN B. CURTIS, citizens of the United States of America, residing at Chicopee Falls, in the county of Hampden and State of Massachusetts, have invented new and useful Improvements in Cover-Locking Devices for Cotton-Beaters, of which the following is a specification.

- 10 This invention relates to cotton-beaters and analogous machines, the object being to provide improved devices for preventing the frequent accidents by which those who work on or about said machines frequently have their hands and arms badly injured, and to that end to provide improved devices for locking the cap or cover of the beater-cylinder case and coacting devices for locking the cover of the conduit-section of the case through which 15
- 20 the beaten cotton is discharged or carried away from the cylinder-case, and devices for preventing the rotation of said cylinder when said covers shall be free to be opened, and whereby provision is also made for the free 25
- 25 rotation of said cylinder when both of said covers shall be locked in shut positions; and the invention consists in the peculiar construction and arrangement of the devices whereby said objects are attained, all as hereinafter fully described, and more particularly 30
- 35 pointed out in the claims.

This invention is in the nature of an improvement upon the invention forming the subject-matter of our application now pending and covering the broad subject-matter hereof.

In the drawings forming part of this specification, Figure 1 is a perspective view of that part of a cotton-beater containing the beater devices and of the covered conduit connected therewith having our improved safety cover-locking devices applied thereto. Fig. 2 is a fragmentary perspective view showing parts of the cylinder-cover and of the case of the beater and of the cover of the cotton-conduit and a portion of the latter and illustrating more in detail the construction of and manner of applying our safety devices to the beater and conduit covers.

50 Referring to the drawings, A indicates the body part of the case of the machine in which

the beater devices are inclosed, the latter being indicated therein in dotted lines.

B indicates one of the two bearings of the machine in which the beater-shaft C is supported and is rotated by means of a belt D, connected with any suitable motor devices and running over a pulley E, fixed on said beater-shaft.

F indicates the cotton-conduit, connected to said body part A of the case, through which beaten cotton is conveyed away from said body, and H is the cover of said cotton-conduit, I indicating the beater-cylinder cover on said case-body A.

The above-referred-to cover and cylinder locking devices comprise the following instrumentalities and operate as below described. A bolt-holding base J is firmly secured on one of said bearings B of the beater-shaft C or other part of the machine near one end of the beater-cylinder cover I, and on said base is a sliding bolt K, parallel with said shaft. The end of said cover I, Fig. 2, adjoining the said bolt-holding base J, has a bolt-hole x therein to receive the inner end of said bolt K, a coiled spring o on the latter, between a part of said base J and a finger-bar w, fixed on said bolt, serving to slide the latter and carry one end thereof into said bolt-hole x, when the cover is closed, and thus lock the same in a closed position, as shown in Fig. 1. Said bolt K has a socket or recess n in the side thereof (see Fig. 2) to receive the end of a second bolt r, below described. A disk L, a section of which is shown in Fig. 1, is fixed on said beater-shaft C and has one or more bolt-holes c in the side thereof adjoining the inner end of said sliding bolt K, and the latter, actuated by the spring o, engages said disk and locks the said shaft C against rotary movement when said beater-cylinder cover I is open, as partially shown in Fig. 2. The devices hereinbefore described as cooperating with the beater-shaft C and connected with said bolt-holding base J, including the bolt K and spring o, and the perforated disk L on said shaft, in connection with the beater-cover, form the subject-matter of our pending application for a

55 60 65 70 75 80 85 90 95 100
patent filed April 21, 1899, and renewed July 7, 1899, and therefore are not specifically

claimed herein. The said bolt-holding base *J* has a bracket *m* thereon, which is perforated to receive one end of a second sliding bolt *r*, and the opposite end of said bolt is supported on a two-armed bracket *s*, secured to the side of said cotton-conduit *F*. The said bolt *r* has its lower end formed to enter the said socket *n* in the side of said bolt *K* and a finger-bar *t* thereon for retiring the same from said socket. A coiled spring *u* is placed on said bolt *r* between a pin thereon and one arm of said bracket *s* and serves to hold the end of said bolt in said socket *n*. Said cover *H* of the conduit *F* has a perforated arm *N* secured thereon, and when said cover is closed, as in Fig. 1, the perforation in said arm is in position to receive the uppermost end of said bolt *r*, and thus lock said cover in a closed position, while its lower end engages said bolt *K*, while the latter locks said cover *I* in a like locked position.

The operation of the above-described devices, in connection with the driving-shaft and said two covers *H* and *I* of the machine 25 to prevent the opening of either of said covers while the machine is running, is as follows: The positions of the safety devices shown in Fig. 1 are those occupied thereby when the beater is running—that is to say, the beater-cylinder cover *I* is locked closed by the entrance of an end of the bolt *K* into the bolt-hole *x*, actuated by the spring *o*, and the opposite end of said bolt is clear of said disk *L*, allowing the shaft *C* to rotate. The lower 35 end of the bolt *r* rests against the side of said bolt *K* and is not now engaged in said socket *n*, the latter now being, by the said position of said bolt, not opposite the end of said bar and is thereby so held that its upper 40 end is in engagement with said arm *N* on the cover *H* and locks the latter also in a closed position, and must so remain while the bolt *K* is in engagement with the beater-cylinder cover *I*. To open either of said covers now 45 requires that the machine be stopped by the usual means, after which the bolt *K*, by grasping the finger-bar *w*, may be slid out of engagement with the said cover *I* and into one of the holes *c* in said disk *L*, and in so sliding 50 said bolt *K* the said socket *n* in its side is

brought opposite the end of said bolt *r*, permitting the latter, actuated by said spring *u*, to slide out of engagement with the arm *N* on the cover *H* and permit the latter to be opened and at the same time, by the entrance of its lower end into said socket *n*, locking said bolt *K* in engagement with said disk *L*. Fig. 2 clearly illustrates the last-described positions of said devices, and therefore while said two covers are free to be or are opened the machine cannot be run.

Having thus described our invention, what we claim, and desire to secure by Letters Patent of the United States, is—

1. In a cotton-beater or analogous machine, 65 the combination with a disk fixed on the shaft of the machine having bolt-holes therein, and with the beater-cylinder and conduit covers of the case of the machine, of two bolts, both simultaneously locking said covers in closed 70 positions while the machine may be running, and one of said bolts when slid out of locking engagement with its cover, engaging said disk and holding the same against rotation, and permitting the actuation of said conduit-cover 75 bolt to disengage the same from said last-named cover, substantially as described.

2. In a cotton-beater or analogous machine, the combination with a disk fixed on the shaft of the machine having bolt-holes therein, and 80 with the beater-cylinder and conduit covers of the case of the machine, of two bolts, each movable in one direction by hand, and oppositely by a spring, and simultaneously locking said covers in closed positions while the machine may be running, one of said bolts having 85 a recess in its side and when slid out of locking engagement with its cover engaging said disk and holding the same against rotation, and presenting said recess opposite the end of the second bolt and permitting the spring thereon to so actuate this last-named bolt as to disengage the same from its conduit-cover, and lock the first-named bolt in engagement with said disk, substantially as described.

JOSEPH T. WARD.
JOHN B. CURTIS.
